UNITED STATES PATENT OFFICE.

ANDREW JACKSON SMETTERS, OF CHICAGO, ILLINOIS.

MUSIC OR BOOK HOLDER AND RACK.

SPECIFICATION forming part of Letters Patent No. 601,736, dated April 5, 1898.

Application filed June 23, 1897. Serial No. 642,210. (No model.)

To all whom it may concern:

Be it known that I, ANDREW JACKSON SMETTERS, a citizen of the United States, residing at Chicago, in the county of Cook and State 5 of Illinois, have invented a new and useful Music or Book Holder and Rack, of which the following is a specification.

My invention relates to improvements in music or book holders and racks in which are 10 arms and clasps for grasping and turning the leaves of the book or sheet-music.

The objects of my improvement are to provide a holder or support for book or music whereby the operator can at will turn or 15 turn the sheet without interfering with or otherwise inconveniencing the operator. I attain these objects by the mechanism illustrated in the accompanying drawings, in which—

Figure 1 is a front view of the entire holder. 20 Fig. 2 is a perspective view of the holder. Fig. 3 is a view looking at my improvement from an end view with the end of the base or box A removed and showing parts thereof.

Throughout the respective views similar 25 letters refer to similar parts.

The box (or base) A is inclosed except in front. To this box (or base) A are secured the uprights B C D, and which uprights (or posts) B C D are so secured as to stand on top 30 of the box (or base) A and are braced by the bars e e at top. From the collar g project the cross-beams b b. The collars h' h² are provided with thumb-screws i i for the purpose of firmly securing said collars in position 35 to the uprights B and D, respectively. Said collars h' h² are provided with holes J' J² for the purpose of passing the regulating-cords k k k k through.

The collar L on the upright C is provided 40 with the arms L' and L², and on the ends thereof are secured the clasps L³ and L⁴. The collar M is provided with the long arm M' and the clasp M², secured on the end thereof. On said collar, opposite to said long arm M', is a 45 short arm M³, in which is a hole or holes at the end thereof, and through which hole or holes the cord k is passed after first being passed through the hole J'. Said cord is secured to the short arm M and the loose end thereof 50 carried to and through the hole J² and down through a hole provided therefor in the top of the box (or base) A. The end of said cord

is then properly tensioned and firmly secured to the key O⁴. The other end of said cord k is properly tensioned and firmly secured to 55 the key O'.

The collar M⁴ is provided with the long arm M⁵, and secured to the end of said long arm is the clasp M⁶. Also secured to said collar M⁴ is the short arm M⁷, in which is a hole 60 (or holes) at the end thereof, and through which hole or holes the cord k is passed after first being passed through the hole J'. Said cord is secured at the one end to the arm M⁷ and the loose end thereof carried to and 65 through the hole provided in the top of the box (or base) A. Said cord is properly tensioned and firmly secured to the key O³. The other or first end of this said cord k is, as the other end at O³, firmly secured to the key 70 O². After these cords k k k k are so passed through the respective holes provided in the top of the box (or base) A, and thence through the hole J' of the collar h', and thence through the holes provided in the ends of the short 75 arms m³ and M⁷, and thereto, respectively, firmly secured, and thence carried over and through the hole J² in the collar h² and down through the holes in the top of the box or base A and each respectively secured to the 80 keys (or levers) O', O², O³, and O⁴. Thus by striking the key (or lever) O' the arm M' is thrown over to the opposite side and the key (or lever) O⁴, to which the other end of the cord k k is secured, is forced to an elevated position 85 ready to strike and reverse the arm M', and likewise the same with the other arm M⁵ and the keys or levers O² and O³.

The rail R is provided and so arranged as to hold the book or sheet-music to keep it 90 from slipping off the box. To the back of the box A, are secured the keys (or levers) O', O², O³, and O⁴, and in such manner as, when the cords k k k k are secured to the keys O', O², O³, and O⁴, to turn or reverse the 95 arms M' and M⁵. There may be one or more arms, as M' and M⁵, operated by keys, as O', O², O³, and O⁴, and cords k k k k, or the respective parts may be increased or decreased correspondingly. The operator secures the 100 back sheets (or cover) of the book, at the top thereof, by the clasps L³ and L⁴, and likewise secures the leaves to be turned to the clasps M² and M⁶, so that when desired by the opera-

tor the respective leaves may be turned or reversed at will by striking the key O' or O² or O³ or O⁴.

What I claim as my invention, and desire 5 to secure by Letters Patent, is—

The combination in a book and music holder and rack, with a box A of uprights B, C, D, firmly secured thereon, said upright C being provided with collars g, bearing the arms f, 10 f, and collars L, M, M¹; the collars L, M, M¹

being provided with arms L', L², M', M³, said arms bearing clasps L³, L⁴, M², M⁶, said arms M', M⁵ being movable around the upright C, the cords k, k, k, k, and the keys O', O², O³, O⁴, substantially as set forth.

ANDREW JACKSON SMETTERS.
